STEPHEN J. DAVIS, OF WILLIMANTIC, CONNECTICUT, ASSIGNOR OF ONE-FOURTH TO
WILLIAM P. JORDAN, OF WILLIMANTIC, CONNECTICUT.

METAL SHINGLE.

1,269,583.

Specification of Letters Patent. Patented June 18, 1918.

Application filed July 31, 1917. Serial No. 183,774.

To all whom it may concern:

Be it known that I, STEPHEN J. DAVIS, a citizen of the United States, residing at Willimantic, in the county of Windham and State of Connecticut, have invented a new and useful Metal Shingle, of which the following is a specification.

The invention relates to a shingle, and more particularly to the class of metallic corner or angle shingles for hip-roofs.

The primary object of the invention is the provision of a shingle of this character, wherein the corner or angle of a hip-roof is conveniently formed therewith to materially strengthen the same and to render the roof at this point water-tight, the shingles in the courses being readily laid with despatch, and without the necessity of weakening such shingles next to the corner shingles by cutting through the butts thereof at an angle with the possible splitting of the same.

Another object of the invention is the provision of a shingle of this character, wherein minimum time is required to fit and lay the shingles both at the corner or angle of a hip-roof and throughout the area thereof in courses, the shingles at the corner or angle being securely held in place, and prevented from curling, warping or loosening at their meeting edges with the shingles in the courses.

A further object of the invention is the provision of a shingle of this character, which is extremely simple in construction, thoroughly reliable and effective in its purpose, a protective closure and ornamental finish at the angle formed by the meeting edges of shingles at a corner or angle of a hip roof, the shingle being practically indestructible and also inexpensive to manufacture and install.

The invention will be best understood from a consideration of the following detailed description, taken in connection with the accompanying drawing forming part of this specification, with the further understanding that while the drawing shows a practical form of the invention, the latter is not confined to any strict conformity with the showing of the drawing, but may be changed and modified so long as such changes and modifications come within the scope of the appended claims.

In the accompanying drawings:

Figure 1 is a fragmentary perspective view of the corner of a shingled hip-roof having the metal shingles constructed in accordance with the invention.

Fig. 2 is a fragmentary detail sectional elevation through the corner shingle.

Fig. 3 is a view similar to Fig. 1, partly in section, taken on the line 3—3 of Fig. 1.

Fig. 4 is a perspective view of one of the corner shingles detached.

Fig. 5 is a view similar to Fig. 4, looking toward the under side of the corner shingle.

Similar reference characters indicate like parts in all of the several views of the drawings.

Referring to the drawing in detail, A and B designate the two sides of a hip-roof, whose meeting edges form the so-called "hip" or corner of said roof. In constructing the roof, the ordinary wooden shingles 10 are employed, which are laid in courses along the sides A and B, respectively, while at the "hip" or corner of the roof are laid the metallic corner or angle shingles, hereinafter fully described.

The corner or angle shingles each comprises a substantially diamond-shaped body 11 made from a single piece of sheet metal, which is bent longitudinally upon a central line at an angle corresponding to the angle formed by the corner of the roof, to which the shingle is to be applied. The body 11 longitudinally bent on the central line presents the angle portions 12 conforming to the sides A and B shingled with the ordinary wooden shingles 10 and marginally of these angled portions 12 of the body 11 are the side and end flanges 13 and 14 respectively, which constitute walls of the body 11, which preferably tapers from the wider walled end 14 to the opposite end thereof. The end flanges 14 are of a thickness corresponding to the butt end of the wooden shingles 10, while the side flanges 13 gradually decrease in thickness from the end flanges 14 toward the smaller end of the body corresponding to the thickness of the wooden shingle 10 from its butt end to its opposite end, so that when the corner or angle shingles are laid with the wooden shingles 10 the outer surfaces thereof will be substantially flush with each other in the successive courses of the shingles.

The side flanges 13 of the body 11 have formed thereon laterally extending securing or base wings 15, which are co-extensive with the side flanges 13 and are formed with 5 suitable holes 16 for the reception of nails or other like fasteners to secure the shingle in place.

The formation of the body 11 of the shingle renders the same hollow, so that 10 when the corner or angle shingles are laid, there is provided a ventilating space under each of the said corner or angle shingles, so as to avoid undue accumulation of moisture therebeneath and the resultant decaying of 15 the wooden shingles or sheathing overlaid by said metal shingles.

In order to apply the metal corner or angle shingles, each of the same is placed in position at the "hip" or corner to overlap 20 the wooden shingles last laid at the corner or "hip" and then is nailed in position. This enables the courses of the wooden shingles 10 along the sides A and B or the "hip" roof to be conveniently laid with despatch 25 and avoids the necessity of cutting the shingles 10 next to the metal corner or angle shingle through the butt end, as only a portion of these shingles are cut away or a corner thereof remote from the butt end, so 30 that the said shingles are not weakened with resultant possible splitting thereof.

The operation of shingling is as follows:

The bottom course of shingles is laid in the usual way and this course includes 35 double shingles superimposed one upon the other. Then a metal shingle is placed in position and nailed at the "hip" line or corner. After finishing this particular course another metal shingle is placed in position 40 at the "hip" or corner line and the operation of laying the next course is repeated until the roof is finished. It is, of course, to be understood that the metal shingles are to be laid before the abutting wooden shingles. The wings 15 of the several metal 45 shingles are successively covered, as the successive courses of wooden shingles are laid.

The manner of swaging the single piece of metal to form the metal shingles provided with the butt end wall 14 and the side wall 13 produces a hollow shingle, which has maximum strength and in the outward appearance thereof simulates the ordinary wooden shingle. While reference 50 has been made generally to the use of wooden shingles with the metal shingles, it will be obvious that slate shingles could be used with equally good result.

The use of metal shingles may be readily 55 disguised by painting or staining the same

in imitation of the wooden shingles, or on the contrary a pleasing contrast may be produced by painting the metal shingles a color in imitation of tiling.

From the foregoing, it is thought that the construction and manner of operation of the invention will be clearly understood, and, therefore, a more extended explanation has been omitted.

What is claimed is:—

1. A metallic shingle for the hip or corner of a roof, comprising a body having flanged edges which elevate the body to substantially the same height as the remaining shingles of the roof and provide a ventilating space beneath the same, the side flanges abutting the edges of the adjacent shingles and the end flanges coinciding with the lower ends of said shingles, and means for fastening the metallic shingle in place. 7

2. A metallic shingle for the hip or corner of a roof, comprising a body formed from a single piece of metal bent longitudinally to provide angular portions, depending side and end flanges on the body, and 8 outwardly extending lateral wings on the side flanges and coextensive therewith.

3. A metallic shingle for the hip or corner of a roof, comprising a body formed from a single piece of metal bent longitudinally to provide angular portions, side and end flanges on the body, and lateral wings extending outwardly from the side flanges beyond the body for the fastening of the latter, and to permit the overlapping of shingles adjacent thereto upon the wings. 95

4. A metallic shingle for the hip or corner of a roof, comprising a substantially diamond-shaped body bent longitudinally to conform to the angle of the hip or corner, angular sides of gradually reduced thickness, and laterally extending wings projecting outwardly from said sides. 10

5. A metallic shingle for the hip or corner of a roof, comprising a substantially diamond-shaped body bent longitudinally to conform to the angle of the hip or corner, angular sides on the body of gradually reduced thickness, laterally extending wings projecting outwardly from said sides, and 11 angular ends meeting each other and the sides.

In testimony, that I claim the foregoing as my own, I have hereto affixed my signature in the presence of two witnesses.

STEPHEN J. DAVIS.
